UNITED STATES PATENT OFFICE

2,638,682

MARKING TOOL FOR LOCATING STRIKE PLATES

Fred J. Russell, Beverly Hills, Calif., assignor, by
mesne assignments, to Loyola University Founda-
tion, Los Angeles, Calif., a nonprofit corpo-
ration of California.

Application April 3, 1950, Serial No. 153,615.

2 Claims. (Cl. 33—197)

1

My invention relates to a marking tool for locating the position of strike plates on door frames of bore-in type lock combinations.

Conventionally such a lock is mounted in a door and the cooperating strike plate is mounted on the door frame. The correct location of the strike plate with reference to the latch bolt of the lock is critical for satisfactory functioning of the lock and strike plate combination. The straight edge of the central opening in the strike plate which engages the latch bolt must not only register vertically with the latter but must have a horizontal location such that when the door is fully closed against the stop the flat side of the latch bolt will advance past the straight edge of the strike plate and be retained by the latter against door opening movement until the latch bolt is withdrawn. Clearance between the latch bolt and straight edge must be at minimum, only enough to assure easy travel of the latch bolt in or out, any excessive clearance resulting in a loose and rattling door, and insufficient clearance rendering advancement of the latch bolt impossible and therefore preventing the door from being locked shut.

In conventional practice the first step is to install the lock in the door. Measurements are then taken vertically and horizontally to locate as accurately as possible the proper position on the door frame for mounting the strike plate. This also involves the forming of a cut-out for the strike plate and a hole extending inwardly from the cut-out to accommodate the latch bolt. There has been no tool or satisfactory method for making the measurements and locating the position of the strike plate. At best the measurements have been approximate, with the result that while in some cases the locations have proved to be accurate, in other installations it has been necessary to employ a trial and error method, sometimes removing the strike plate and moving it higher or lower, or in or out. When this has to be done sometimes part of the cut-out in the frame is exposed, sometimes the new location of the wood screws holding the strike plate in is so close to the original position of the screws that torn enlarged screw holes result and the attachment is unsecure. These and other conditions often result in an unworkmanlike job.

The object of my invention is to overcome the difficulties indicated, more specifically, to provide a special marking tool which can be inserted into the hole prepared in the door for the bore-in lock and while being guided by the wall of the hole may be driven against the door frame with

the door in fully closed position for the purpose of marking the location for the strike plate.

The mark in the door frame may be used as the index for a circular hole to be bored, which latter in turn will provide the index for a conventional mortising tool which will make in the correct location the rectangular cut-out required by the outline of the strike plate; or the original mark on the door frame may be used as the index to first make a rectangular cut-out for the strike plate and then utilizing the mark as a center for boring a hole. In both cases, the hole ultimately serves to provide the required clearance in back of the strike plate opening through which the latch bolt passes.

The foregoing and additional objects of the invention will become apparent from a further consideration of the description taken in conjunction with the drawings.

20 In the drawings:

Figure 1 is a perspective view of my special marking tool.

Figure 2 is a side view of the marking tool shown in position for marking a door frame.

25 Figure 3 is a fragmentary perspective view partly in section of the frame of Figure 2 marked for locating the strike plate.

Figure 4 is a horizontal cross section of a frame assembly as shown in Figure 2 illustrating the use of a bit in utilizing the mark shown in Figures 2 and 3.

30 To explain in more detail the purpose and function of my tool, reference is made to Figure 2, wherein a door 20 is adapted to be closed adjacent to a door frame 21 against a stop 22 secured to the frame. Trim 23 on the frame is included in the illustration merely to complete the showing.

35 A hole 24 is bored through the door and a hole 25 is bored from the edge of the door through to intersect with the hole 24. Most standard bore-in locks are made of dimensions which ordinarily call for the hole 24 to be of a two inch diameter and the hole 25 to be of a one inch diameter. These measurements are by way of illustration only and are referred to only because they apply to present standards. Reference to such dimensions hereinafter is for the purpose of identification only and not of limitation. The length of the bore of the hole 25 is sufficient to provide sufficient longitudinal wall surface that an element which fits the bore can be axially guided without wobbling.

40 My special marking tool 26 comprises an annular plug or piston-like body 27 with a flat for-

ward end face 28 preferably from the center of which extends a pointed punching element 29. This element 29 is preferably of circular tapered shape so that when driven into the surface of a wood frame it will make a conical indentation 30. The exact dimensions of the punch element and the consequent indentation are not critical but the indentation, of course, will correspond to the size and shape of the punch element and it is preferable that the indentation be of a character to receive the pilot point of a drill bit, as shown in Figure 4, or the tapered point of a mortising tool (not shown).

The rear end of the marking tool is preferably provided with a tapered end shoulder 31 to facilitate inserting the tool into the bore hole in the door from the outside. A short stem 32 forms the rear terminal end of the tool and provides an annular notch 33 between the annular surface of the stem 32 and the flat end portion 34, which notch is suitable for engagement by a tool, as for example a screw driver 35, which can be inserted angularly through the hole 24 in the door. A blow struck against the screw driver or some other rigid tool when positioned as shown in Figure 2 will drive the marking tool 26 forwardly into contact with the door frame and cause the punch element 29 to make the mark 30 illustrated in Figures 2 and 3.

It is important that the diameter of the piston-like body 27 be approximately the same as the diameter of the hole 25, at least the respective dimensions be sufficiently close that the hole which is ordinarily somewhat elongated like a cylinder will provide a snug fitting guide for the marking tool whereby the indentation mark when made will be accurately located. The length should be greater than the length of the bore hole 25 so that the rear end of the tool is accessible through the side hole 24. Ordinarily when the diameter of the tool body 27 is approximately one inch, the length will be approximately two inches.

The tool may be of any suitable material but ordinarily a case hardened steel or tool steel gives the best results.

In Figure 4 is shown the use of a drill bit 40 boring what will ordinarily be a one inch hole 41 in the door frame to provide the necessary space for the latch to enter through the strike plate. The cut-out for the strike plate, shown in broken lines in Figure 3, may be formed by a mortising tool or chisel before or after the hole 41 is bored. A mortising tool may be employed which has a guide pin that is caused to register with the indentation mark 30 or caused to register with the hole 41 which has been bored with the indentation mark 30 acting as a center.

While I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

The forward end need not have a flat face as illustrated, the essential thing being the presence of a punch or marker which will make either a small indent mark or cut which is distinguishable.

The rear end need not be shaped with the

particular annular notch shown. If a straight tool such as a screwdriver or a conventional center punch is to be used, it is desirable to embody in my marking tool, the annular notch, or some equivalent comprising a depression or a lug or other stop against which the screwdriver or center punch may engage.

The plug or piston-like body need not be truly cylindrical, but can be modified provided the diametrical surface extremities will slidably engage and be guided by the wall of the bore hole 25 which is cylindrical.

Having described my invention, what I claim as new and desire to secure by Letters Patent is:

1. A method of mounting respective parts of bore-in lock hardware respectively in a door and frame therefor by employment of a marking tool of selected length and diameter comprising boring a side hole in the door at a point spaced from a free swinging edge thereof, boring a bore hole at the same level in the free swinging edge from the edge to meet the side hole, selecting a marking tool of diameter providing a snug sliding fit in the bore hole and inserting said marking tool from the edge into the bore hole to a position wherein one end is exposed to the side hole and the other end is within the surface of the edge, closing the door to a stop position in the frame and there driving said marking tool outwardly to effect a score on the frame, then with the door withdrawn from the frame boring a bolt hole in the frame in a location which corresponds to the score for locating a strike plate accurately in position.
2. A method of mounting respective parts of bore-in lock hardware respectively in a door and frame therefor by employment of a marking tool of selected length and diameter comprising locating a relatively larger side hole in the door at a point spaced from a free swinging edge thereof and boring said side hole, locating a relatively smaller bore hole at the same level on the free swinging edge and boring said bore hole from the edge to meet the side hole, selecting a marking tool of diameter providing a snug sliding fit in the bore hole and inserting said marking tool from the edge into the bore hole to a position wherein one end is exposed to the side hole and the other end is within the surface of the edge, closing the door to a stop position in the frame and there driving said marking tool outwardly to effect a score on the frame, then with the door withdrawn from the frame outlining a strike plate cut-out pattern on the frame surrounding the score, boring a bolt hole in the frame, the bolt hole being in a location which corresponds to the score, and clearing the cut-out pattern for locating the strike plate accurately in position.
